UNITED STATES PATENT OFFICE.

LONNIE C. COLE, OF ALLENDALE, SOUTH CAROLINA, ASSIGNOR OF ONE-HALF TO
CLARA B. HARDEN, OF ALLENDALE, SOUTH CAROLINA.

DOORSTOP LATCH.

Application filed June 4, 1928. Serial No. 282,779.

My invention relates to door stops or holders, designed to lock or secure the door in open position so as to prevent it being accidentally closed by wind or otherwise.

5 The object is to provide a latch door holder or stop of the character mentioned which may be made at small cost, and readily applied without necessarily employing skilled labor and which will be efficient for the purpose in view.

10 To the accomplishment of the foregoing and such other objects as may hereinafter appear, the invention consists in the features herein illustrated and described, and then 15 sought to be clearly defined by the claims, references being had to the accompanying drawing forming a part hereof, and in which

20 Figure 1 is a front elevation of part of a barn, garage, or other building, with one door closed and another partially opened, showing the present invention applied thereto;

25 Figure 2 is a perspective view, enlarged scale, showing the position of the stop or holder with a door partially opened;

Figure 3 is a plan view of another form of stop or holder.

30 In the drawing, the numeral 1 designates the upper portion of a barn, garage, or other structure, 2 doors thereof, and 3 door-hinges. The latch holder or stop comprises a member or bar 4 formed with a bow-member 5 formed with teeth 6 along its lower edge, one side of which is beveled or inclined as 35 at *a* and the other side preferably straight as at *b*, the spaces between the teeth being substantially the width of the thickness of the door so as to receive the top edge of the door and hold the door by the teeth adjacent thereto when the door is opened or partially 40 opened, as illustrated in Fig. 2 and at the right of Fig. 1 of the drawing. The base member or bar 4 is provided with a suitable hinge by which it may be attached to the door frame of the building as illustrated in 45 Figs. 1 and 2 of the drawing. The hinge preferably comprises a knuckle 7, preferably formed integral with the bar and a leaf member 8 having knuckles 9, and a pintle 10 passed through the knuckles as illustrated.

50 The latch stop hinged to the door frame as mentioned is free to rise and fall as the door is swung into open position, the edge of the door striking against the inclined side of the teeth will lift the latch which may then drop

by gravity to receive the edge of the door and hold it in its open position as illustrated, and prevent it from being accidentally closed by wind or otherwise. When the door is to be closed, the latch may be raised by suitable means, say by a cable 11 which will be connected at one end to the latch and passed over a pulley 12 and then down to within easy reach of an individual desiring to operate the door. By producing a hook (not 60 shown) at an appropriate part of the door or its frame, the free end of the cable may be connected thereto so as to retain the latch in its raised position if desired.

65 Under the construction described, the latch will be automatically released as the door is swung open and it will be held in raised or unlatched position as the door is being swung into closed position. To prevent defacing the door by the latch, the door 70 may be provided with a metal facing along the portion where it will be engaged by the latch, such facing being afforded by a metal-plate or plates 13 attached to, or set into the door, at one or both facings, as illustrated.

75 It is preferred to form the base or bar 4 and bow-member 5 in one piece as shown in Fig. 2 of the drawing, but the bow-member and bar may be made of separate pieces and riveted or otherwise connected together as 80 shown in Fig. 3 of the drawing.

85 The latch stop illustrated and described may be used with double doors as shown in Fig. 1 of the drawing, by use of two of the latches, or with a single door, opening to the right or to the left by use of a single latch as will be obvious from an inspection of Fig. 1 of the drawing. In either case, a person using a garage may have the door held in open position while driving in or 90 out of the garage without being annoyed by the door swinging into closed position by wind, or otherwise. The latch is also comparatively inexpensive to construct, and conveniently operated, and can be applied without 95 employment of a skilled mechanic or workman.

100 I have illustrated and described the preferred details of parts, but changes can be made therein without departing from the essential features of the invention as sought to be defined by the appended claims.

105 Having described my invention, and set forth its merits, what I claim is:—

110 1. A door latch comprising a hinged mem-

ber having teeth along its lower edge, one side of the teeth being beveled for engagement of one edge of a door therewith for automatically lifting the member in swinging the door open, the opposite side of the teeth being formed as a shoulder to constitute a stop to prevent the door closing until the hinged member is manually raised.

2. A door latch comprising a hinged bar for attachment to a door frame and provided with a bowed member having teeth along one edge for engagement with the opposite faces of the door along one edge thereof when in opened position, said teeth having one side beveled for automatic lifting of the latch by engagement of the door with the beveled side of the teeth in swinging the door to open position, the opposite side of the teeth being formed as a shoulder to constitute a stop to prevent the door closing until the hinged

bar is manually raised and means for disengagement of the latch with the door when the door is to be closed.

3. The combination with a door, of a hinged latch member having teeth along its lower edge, the teeth having a beveled side for engagement of the edge of the door therewith in swinging the door to open position, the opposite side of the teeth being formed as a shoulder to constitute a stop to prevent the door closing until the hinged latch member is manually lifted, a protecting facing-plate on the face of the door to protect the door from defacement by engagement of the teeth therewith, the latch member being lifted by engagement of the door edge with the beveled side of the teeth in swinging the door.

In testimony whereof I affix my signature.

LONNIE C. COLE.
